Patented Dec. 12, 1922.

UNITED STATES PATENT OFFICE.

LOUIS P. BOLANDER, OF SAN FRANCISCO, CALIFORNIA.

FLAGPOLE.

Application filed June 21, 1922. Serial No. 569,770.

To all whom it may concern:

Be it known that I, LOUIS P. BOLANDER, a citizen of the United States, residing at the city and county of San Francisco, and 5 State of California, have invented certain new and useful Improvements in Flagpoles, of which the following is a specification.

The hereinafter described invention relates to an improved construction of flagpoles designed for use more particularly in connection with school buildings, playgrounds, parks and buildings generally; the object of the invention being the production of a flag-pole which permits of raising and 10 lowering with a swinging movement, one wherein the climbing thereof for purposes of painting is eliminated and, so disposed relative to its base supporting structure that when swung into vertical position there is 15 presented to the eye the appearance of an integral structure and the stub of the pole 20 being substantially hidden from view.

To comprehend the invention, reference should be had to the accompanying sheet of 25 drawings, wherein—

Figure 1 is a part broken perspective view of the pole in raised position, the position thereof when lowered being illustrated in dotted lines.

Figure 2 is a broken detail view of the pole, one of the side plates of the housing for the stub of the pole being removed and the stub in vertical section on the line 2—2—Fig. 3 of the drawings, for illustrating the preferred manner of applying counter-balance means thereto.

Figure 3 is a broken detail front view of the pole with its stub fitted within the housing therefor.

Figure 4 is a transverse sectional plan view taken on the line 4—4—Fig. 2 of the drawings.

Figure 5 is a view similar to Fig. 4, taken on the sectional line 5—5—Fig. 2 of the drawings.

In the drawings, the housing for the stub 1 of the pole 2 is composed of the spaced vertically disposed side plates 3 and the face angle plate 4, which is united to the side 50 plates 3 in any suitable manner to provide a substantially rectangular shaped housing for the reception of the stub 1 of the pole 2, when the same stands in vertical position.

The face plate 4 in the present case is of 55 a length slightly less than the side plates 3 and between the projecting end portion of

the said side plates the pole 2 is mounted for swinging movement by means of the transversely disposed bolt 5 which passes through the side plates and the said pole. 60 In the present case, the pole 2 is balanced by means of removable weights 6, which in shape conform to the interior of the stub housing and are secured to the lower end of the pole stub 1 by means of the securing bolt 65 rod 7. The said rod passes through an opening formed in each of the weight sections 6 and within a longitudinal bore 8 formed for a distance within the lower end of the stub 1, said bore being intersected by 70 a transverse bore 9 within which is fitted a securing nut 10 for receiving the upper screw threaded end of the securing bolt 7. The lowermost weight of the weight sections 75 11 is formed with a counter-sunk socket 11 to receive a bolt 12 which screws onto the lower projecting screw threaded end of the securing bolt 7. As many weight sections 6 are employed as is required to provide the requisite weight for counter-balancing the projecting end of the pole 2, each 80 section 6 being of a given weight. While preference is given to the employment of removable weight sections 6 for counter-balancing the weight of the pole 2, it is apparent that any desired form of counter-balancing means may be employed for such 85 purpose.

Within that portion of the stub housing as fits within the ground—where the pole 90 is employed in connection with playgrounds and parks or is designed to be secured to supporting means when the pole is applied to buildings,—there is placed a vertically disposed filling plug 13, the upper 95 face 14 of which is formed at an upward inclination. The exposed bottom face 15 of the lowermost weight section 6 is inclined in a direction opposite to that of the exposed top of the filling plug 13 in order 100 to register therewith as the flag-pole is swung into vertical position, the inclined faces 14 and 15 serving as wedging means for holding the pole 2 in said vertical position.

When the pole 2 stands in raised position, the same is held locked to the housing for the pole by means of the transversely disposed securing bolts 16 which pass through the housing and the stub 1, being 110 held in place by the securing nuts 17.

The angle plate 4 being riveted to the

inner faces of the side plates 3, gives rigidity to the housing for the stub 1 of the pole 2.

Inasmuch as the fulcrum point for the 5 flag-pole is situated relatively a short distance above the foundation for the pole, the said pole may be easily swung into vertical and horizontal positions.

By the described constructed and mounted 10 flag-pole, the same may be quickly swung into horizontal or lowered position for painting, cleaning or other purposes and afterwards placed into vertical position, the cost of erection of the pole is reduced to 15 a minimum, and a strong housing is provided for the stub of the pole, which, when the pole stands in vertical position, presents a neat and attractive appearance.

Having thus described the invention what 20 is claimed as new and desired to be protected by Letters Patent is:—

1. The combination with a flag-pole adapted for swinging movement, of a housing shaped to conform to the stub of the 25 pole and comprising spaced side plates and an angle face plate united thereto, said housing adapted to be held to the foundation for the pole, a filling block fitted within the lower portion of the housing having 30 an inclined upper end, means whereby the pole is fulcrumed between the side plates

of the housing at a point above the angle face plate thereof, counter balance means for the pole applied to the stub thereof, the lower face of the stub adapted to register 35 with the inclined face of the filling block of the housing when the pole is swung into vertical position, and means for locking the stub to the housing when the pole is so positioned.

2. The combination with a flag-pole, of a housing adapted to receive the stub of the pole, comprising spaced side plates and an angle face plate, said housing adapted to be held to the foundation for the pole, a 45 filling block fitted within the bottom portion of the housing provided with an inclined upper exposed face, a series of counter-balancing weights adapted to fit within the housing, means for detachably uniting the weight to the stub of the pole, the bottom face of the lowermost weight of the series being shaped to register with the inclined exposed face of the filling block, means for fulcruming the pole between the 55 projecting portion of the side plates for the housing, and devices for locking the stub of the pole within the housing when the pole stands in vertical position.

In testimony whereof I have signed my 60 name to this specification.

LOUIS P. BOLANDER.
